UNITED STATES PATENT OFFICE.

CORLISS T. COLBY, OF THORP, WISCONSIN.

GATE-LATCH.

1,174,945.

Specification of Letters Patent. Patented Mar. 7, 1916.

Application filed March 10, 1915. Serial No. 13,427.

To all whom it may concern:

Be it known that I, CORLISS T. COLBY, a citizen of the United States, residing at Thorp, in the county of Clark and State of Wisconsin, have invented certain new and useful Improvements in Gate-Latches, of which the following is a specification.

This invention relates to doors, gates, and the like, and more particularly to a new and improved latch means therefor.

The primary object of my invention resides in the provision of a latch which will automatically unlock when force tending to open the gate or door is applied to the handles thereof.

A further object of my invention resides in the provision of a peculiarly constructed handle means for operating the latch, and a peculiar "strike," the latch means being so connected with the handles that the same is automatically disengaged from the "strike" when the handles are grasped to open the door or gate.

A still further object of my invention is to attain the above-set forth objects with a structure which is simple, cheap to manufacture, effective in operation, and one which is strong and durable and readily applicable to use in connection with the various forms of doors now in common use.

Another valuable feature of my invention resides in the fact that sagging of the door to which the device is applied is taken care of by the peculiar construction provided.

With the above and other objects in view my invention resides preferably in the construction, combination, and arrangement of parts as hereinafter set forth in the specification and illustrated in the accompanying drawings, in which—

Figure 1 is a fragmentary front elevation of a door and door frame showing the application of my improved latch. Fig. 2 is a top plan view partly in section of the same. Fig. 3 is a detail view of the handle member detached. Fig. 4 is a rear elevation of an improved protective casing which I provide.

Similar reference characters indicate similar parts throughout the various views of the drawings.

Referring more particularly to the drawings in which the preferred embodiment of my invention is illustrated, the numeral 1

indicates the door, gate, or the like, which is preferably of the hinge type, and a portion 55 of the door frame is designated 2. My improved latch means comprises three component parts, namely, a latch member, an operating handle, and spring means for returning the latch to a normal position. The 60 handle member comprises preferably a strand of wire having one of its extremities formed to provide one handle portion 3, the intermediate portion of said strand of wire being offset to provide a second handle portion 4, and bearing portions 5 and 6 adjacent said handle portion 4. The other extremity of the strand of wire is bent to form a crank portion 7. The above described structure is mounted vertically for rotation 70 in bearing brackets 8 and 9 which are adapted to receive the rotatable support or bearing portions 5 and 6 of the strand of wire which forms the operating means. The brackets 8 and 9 are provided with feet 10 75 and 11, respectively, which facilitate securing of the same to the face of the door 1. A portion 6' of the strand of wire extends through an elongated slot 12 in the door 1 so that the handle portion 3 is disposed on 80 one side of the door and the handle portion 4 on the opposite side thereof. In order to prevent vertical movement of the operating means in the brackets 8 and 9 collars 13 are mounted on the bearing portions 5 and 6, 85 respectively, disposed below and above the brackets 8 and 9 as shown to advantage in Figs. 1 and 2.

The latch member hereinbefore referred to comprises an arm 14 having one extremity 90 thereof enlarged as shown at 15 and engaged over the crank portion 7. The said arm 14 is mounted intermediate its length in a guide bracket 16 carried by a base plate 17 bolted or otherwise secured to the door 1. The arm 95 14 is slidably mounted in said bracket 16 and the outer extremity of said arm 14 is bent laterally to provide a substantially right angular portion 18 having an enlargement forming an engaging pawl 19 on the 100 extremity thereof.

The latch, as a whole, has been shown in normal locked position, this being accomplished by means of a retractile spring 20, one extremity of said spring 20 being secured in a guide bracket 21 bolted or other-

wise secured at 22 to the door 1 and the opposite extremity of said retractile spring 20 is connected through the medium of a guide rod 23 at 24 to the crank portion 7 as shown 5 to advantage in Figs. 1 and 2. One extremity of the guide rod 23 is mounted for slidable movement in the guide bracket 21 as indicated at 25. It is preferable that the 10 guide brackets 16 be of a slightly larger size than the width of the latch member 14 so that a slight lost motion may be allowed for the same owing to the arcuate path of travel of the crank 7 and the same might be said of the guide bracket 21 relative to the guide 15 rod 23.

Any suitable means may be provided on the door frame 2 for engagement of the extremity of the latch arm 14, but I have provided a strike which consists of an elongated plate 26 secured by screws or the like 20 to the door frame 2. The said plate 26 is provided with a central aperture 28 registering with an aperture 29 formed in the door frame 2. One marginal edge of the 25 aperture 28 is rounded as indicated at 30 by depressing the metal of the plate 26 along this marginal edge so as to provide a shoulder against which the pawl portion 19 of the latch arm 14 may engage as shown 30 to advantage in Fig. 2. It will be noted that the strike plate 26 is vertically disposed on the door frame 2 and is of a relatively great length. This provides for the sagging of the door, warping or similar 35 other defects which the action of the elements cause, as it will be seen that should the door sag, the extremity of the latch arm 14 will, nevertheless, engage at all times with the distorted edge 30 so that the door 40 may be effectively locked regardless of its sagging, which under other conditions would render useless the latch.

I provide a protective casing 31 which is adapted to be secured above the retractile spring 20 by screws 32, or otherwise, so as to afford an inclosing chamber to prevent the weather from rusting the connections.

While I have described my invention as applied to a door, it will be readily understood that its uses are not at all limited, but it will be found particularly adapted for use in connection with barn doors, silo doors, gates, and the like, wherein the same 55 are very often exposed to the severest weather conditions.

It is thought that the construction, operation, and advantages of my invention may be readily gathered from the above description taken in connection with the accompanying drawings and it will be noted that by grasping the handle 4 and directing a pull thereon to open the door, the said handle 4 will move in the direction described by 65 the dotted arc, causing the crank portion

7 to impart a thrust to the arm 14, causing the same to move to the dotted position shown in Fig. 2, thereby unlocking the same and allowing the door to be opened. Upon releasing the handle 4, the retractile spring 20 will draw the latch arm 14 back into the position shown in Figs. 1 and 2. In order to latch the door or gate, as the case may be, it is only necessary to swing the same into closed position, the pawl portion 19 riding over the edge 30, the retractile spring 20 again acting upon the same to enforce positive engagement of the pawl portion 19 with the said edge 30. The operation from the other side of the door will be slightly 80 different, that is, the handle 3 must be grasped and moved in the direction indicated by the dotted arc, and will perform the same function as the handle 4.

While I have shown and described my invention as possessing a peculiar form and construction, it is desired that it be understood that I may make such changes in the details thereof that do not depart from the spirit and scope of the invention as claimed.

Having thus described my invention what I claim and desire to secure by Letters Patent is.

1. A gate latch, including, in combination with a gate, a latch arm reciprocally mounted on said gate, a retractile spring associated with the latch arm, a pair of operating handles formed from a single strand of wire having a crank portion associated therewith for pivotal engagement with said latch arm, said spring being connected adjacent the jointure of said crank with said latch arm, and means for supporting said handles to operate laterally of the door.

2. A gate latch including, in combination with a gate, a latch member slidable on the gate, spring retracting means therefor, and an operating handle rotatable on said gate having a crank portion pivotally connected with said latch member and operable from either side of the gate.

3. The combination with a gate and a latch member thereon, of an operating member formed of a strand of wire having handle portions and a crank portion, said crank portion having pivotal engagement with the latch member and a spring acting upon said crank and said pivot.

4. A gate latch, including, in combination with a gate, a latch arm reciprocally mounted on the gate, an operating member therefor vertically journaled on the gate and provided with a pair of manipulating handles extending on opposite sides of the gate, and a crank formed integral with one end of the operating member.

5. A gate latch, including, in combination with a gate, a latch arm reciprocally mounted on the gate, an operating member therefor formed of a single strand of wire bent

to form handle portions and journal portions, said operating member being vertically journaled on the gate and provided with a crank portion, the handle portions 5 thereof extending on opposite sides of the gate, said crank portion being connected with said latch member, and a link connected with said crank portion, said link having

connection with a retractile spring as and for the purpose set forth. 10

In testimony whereof I affix my signature in presence of two witnesses.

CORLISS T. COLBY.
